INTERMITTENT STRIP FEED MECHANISM

Albert S. Howell, Culver, Ind., assignor to Bell & Howell Company, Chicago, Ill., a corporation of Illinois

Application July 22, 1947, Serial No. 762,748

33 Claims. (Cl. 88—18.4)

1

My invention relates particularly to intermittent strip feed mechanism for feeding motion picture film strips provided with the usual feed perforations.

Objects of the invention reside in the provision of a novel, desirable and effective intermittent strip feed mechanism, which is particularly adapted for motion picture projecting machines, which is precise in operation, which is so constructed that the reciprocating structure thereof may have a relatively small amount of momentum, which, involving an oscillating lever for reciprocating the toothed strip feed means of the mechanism, provides a pivotal mounting for the lever which while establishing a pivotal axis for the lever, provides for effecting reciprocation of the feed means connected portion of the lever different from that resulting solely from pivotal movement of the lever on said axis and conforming with rectilinear reciprocation of the toothed strip feed means, which provides for counterbalancing the reciprocating structure thereof, which involves a novel and desirable engagement and disengagement of a toothed reciprocatory feed shuttle with the feed perforations of a strip as an incident of intermittently feeding the strip, which involves a novel and desirable reciprocatory feed shuttle and bearing therefor and a novel and desirable means for actuating the feed shuttle, which provides for convenient assembly adjustment of the mechanism, which provides, preferably as an operating adjustment, for adjusting the extent of the reciprocatory strip feed and return movement of the toothed feed means or feed shuttle to conform with the spacing of the feed perforations of the strip and so accommodate for shrinkage or expansion of the strip, and which provides, preferably as an operating adjustment, for adjustment of the strip feed and return stroking range of the toothed feed means or feed shuttle for "framing."

The invention will be better understood by reference to the accompanying drawing in which—

Figure 1 is a partial sectional view in rear elevation of a motion picture projecting machine embodying my invention;

Figure 2 is a partial sectional view of the same taken substantially on the line 2—2 of Figure 1;

Figure 3 is a vertically condensed perspective view of the feed shuttle of my invention;

Figure 4 is a vertically condensed sectional view in side elevation of the feed shuttle and bearing thereof of my invention taken substantially on the line 4—4 of Figure 5;

2

Figure 5 is a vertically condensed view in front elevation of the feed shuttle and bearing thereof of my invention;

Figure 6 is a partial sectional view taken substantially on the line 6—6 of Figure 1;

Figure 7 is an exploded view of the mounting structure of the shuttle actuating and counterbalance levers of the mechanism;

Figure 8 is a perspective view of one of the frame parts of the mechanism;

Figure 9 is a partial sectional view in rear elevation of the shuttle actuating lever mechanism of the invention;

Figures 10 and 11 are partial sectional views in rear elevation of the adjustable shuttle actuating and counterbalance lever mounting structure of the mechanism and showing the same in different positions of adjustment;

Figure 12 is a sectional view taken substantially on the line 12—12 of Figure 13 and showing the film guide of the machine with a film strip therein and the feed shuttle of the mechanism; and

Figures 13 and 14 are partially diagrammatic views in rear elevation of the intermittent feed mechanism of the invention and a film strip being fed thereby and showing the mechanism in different positions of its operating cycle.

Referring to the drawing, 1 designates a frame part which is disposed vertically and transversely of the machine and is provided with a large circular recess 2 extending inwardly from its rear face. See Figures 1, 2 and 8. The transverse wall of the recess 2 is provided with a rectangular light aperture 3 adjacent the periphery of the recess and disposed upwardly and to one side of the axis thereof. The rear face of the transverse wall of the recess 2 is also provided with a horizontal rectangular recess 4 extending across the axis thereof and terminating at the side of this axis on which the light aperture 3 is disposed with an opening 5 spaced below the light aperture.

The frame part 1 is provided with a forwardly extending bored hub 6 whose bore 7 is disposed concentrically of the recess 2 and communicates with the recess 4. The bore 7 is provided with a counterbore 8 at the inner face of the transverse wall of the recess 4 and the inner face of this recess is provided with another recess 9 communicating with the counterbore 8 and extending horizontally therefrom on the side thereof opposite that on which the opening 5 is disposed, the recess 9 being deepened outwardly beyond the counterbore 8. A cover plate 10 extends across the recess 2 at the rear thereof and forms a

closure therewith as shown in Figure 2, and is suitably secured with the frame plate 1.

An arm 11 is provided with a concentrically bored circular enlargement 12 at one end thereof and the bore 13 of this enlargement is provided with a forwardly disposed flange 14. See particularly Figure 7. The rearward face of the arm 11 is provided with a slot 15 extending radially of the bore 13 and the forward face of this arm is provided with two slots 16 and 17 spaced radially of the bore 13 and extending angularly thereof and communicating with the slot 15. The arm 11 is also provided with a bore 18 therethrough which is parallel to the bore 13 and is disposed between the slots 16 and 17.

The arm 11 is disposed and extends horizontally within the counterbore 8 and recess 9 with the enlargement 12 within the counterbore 8, and a flanged screwthreaded bushing 19 extends through the bore 13 of this arm and is screwthreaded into the bore 7 and having a spring friction washer 21 engaged thereon, frictionally clamps the flange 14 of the arm and the spring washer between its flange 22 and the shoulder of the counterbore 8, thus providing a friction bearing on which the arm 11 is pivotally mounted coaxially of the bore 7 for vertical movement, as shown in Figures 1, 2 and 9.

A plunger 23 is slidably engaged in a vertical bore 24 of the frame part 1 and extending downwardly from the recess 9, and is upwardly engageable with the outer end of the arm 11 as best shown in Figure 9. A helical compression spring 25 within the bore 24 below the plunger 23 reacts on a plug 26 screwthreaded into the lower end of this bore and yieldably urges the plunger 23 upwardly and thus yieldably urges the arm 11 upwardly. A plunger 27 is slidably engaged in a vertical bore 28 of the frame part 1 and extending upwardly from the recess 9, and is downwardly engageable with the outer end of the arm 11. A rod 29 is screwthreaded, as designated at 30, in the bore 28 above the plunger 27 and is engageable downwardly thereon so that rotation of this rod effects in cooperation with the spring 25 vertical pivotal adjustment of the arm 11 on the axis of the bore 7, the rod being provided with a suitable manipulating means, not shown, whereby the arm may be conveniently vertically adjusted during operation of the machine.

A headed stud 31 extends rearwardly through the slots 16 and 15 of the arm 11 in parallelism with the bore 7 and its shank 32 is slidably and rotatably engaged in the slot 15. See Figures 1, 2, 7 and 9. This stud is provided with a portion 33 which is disposed eccentrically of the shank 32 and which is slidably and rotatably engaged with the slot 16, so that angular adjustment of this stud effects adjustment of the shank 32 along the slot 15 and accordingly horizontally and radially of the bore 7.

Another headed stud 34 extends rearwardly through the slots 17 and 15 of the arm 11 in parallelism with the bore 7 and its shank 35 is slidably and rotatably engaged in the slot 15. This stud is provided with a portion 36 which is disposed eccentrically of the shank 35 and which is slidably and rotatably engaged with the slot 17, so that angular adjustment of this stud effects adjustment of the shank 35 along the slot 15 and accordingly horizontally and radially of the bore 7.

The studs 31 and 34 are thus adjustable together vertically by reason of their being car-

ried on the vertically adjustable arm 11, and their shanks 32 and 35 are independently adjustable horizontally and radially of the bore 7 by reason of their being correspondingly adjustably mounted on the arm 11.

An elongated spring plate 37 is provided with bifurcated ends 38 and with an intermediate bore 39, and extends across between the heads of the studs 31 and 34, respectively designated at 41 and 42, and the bifurcated ends of the plate respectively slidably engage a circumferential groove 43 of the head 41 and a shoulder 44 of the head 42. A flanged nut 45 extends rearwardly through the intermediate bore 39 of the spring plate, and a headed screw 46 extends forwardly through the bore 18 of the arm 11 and is screwthreaded into the nut 45, so that the spring plate 37 frictionally clamps the heads of the studs 31 and 34 rearwardly against the arm 11 to the end that the studs may be adjusted on the arm and retained in adjusted position.

A short shaft 47 extends forwardly from the stud 31 in approximate alinement therewith and is rotatably mounted in a bore 48 of the frame part 1, and is provided at the end thereof which faces this stud, with a pair of diametrically opposite radially extending drive lugs 49. See Figures 2 and 7. The head 41 of the stud 31 is also provided with a pair of diametrically opposite radially extending drive lugs 51, and a drive disk 52 is disposed between the shaft 47 and head 41 and is provided with two pairs of diametrically opposite radially extending drive slots 53 disposed at an angle of ninety degrees and respectively slidably engaged with the drive lugs 49 and 51 to provide a drive connection between the shaft 47 and stud 31 of the "Oldham" type which permits radial movement of the stud 31 relative to the shaft. Another shaft 54, disposed transversely of the shaft 47, is rotatably mounted in a bore 55 of the frame part 1 and is provided with a worm gear 56 which meshes with a spiral gear 57 formed on the shaft 47 for rotating this shaft with rotation of the shaft 54, the shaft 54 being provided with a suitable manipulating means, not shown, whereby the stud 31 may be angularly adjusted to adjust the shank 32 of this stud along the slot 15 of the arm 11 during operation of the machine.

The head 42 of the stud 34 is provided with a diametrical slot 58, see Figure 2, which may be engaged by a screw-driver through a bore 59 of the frame part 1 for rotating this stud to adjust the shank 35 thereof along the slot 15 of the arm 11, a headed screw 61 screwthreaded into the bore 59 normally closing this bore.

A pair of bearing rollers 62 are rotatably mounted on the shank 32 of the stud 31 rearwardly of the arm 11 and are retained thereon by a headed screw 63 screwthreaded into the rearward end of the shank 32, see Figures 1, 2, 7 and 9, and another pair of bearing rollers 64 are rotatably mounted on the shank 35 of the stud 34 rearwardly of the arm 11 and are retained thereon by a headed screw 65 screwthreaded into the rearward end of the shank 35, it being observed that these pairs of bearing rollers are independently adjustable along the slot 15 of the arm 11 and accordingly horizontally and radially of the bore 7, respectively, by angular adjustment of the studs 31 and 34.

The studs 31 and 34 and their bearing rollers 62 and 64 are disposed at the side of the bore 7 opposite that at which the opening 5 is disposed, and two substantially identical horizontally dis-

posed levers 66 and 67 of light truss formation extend correspondingly from the rollers 62 in overlying relation to the opposite side of the bore 7 and into the opening 5, the bearing rollers 62 and 64 and the levers 66 and 67 being disposed in the recess 4. See Figures 1, 2 and 9.

The ends of the levers 66 and 67 in the region of the bearing rollers 62 are each provided with straight vertically spaced parallel opposing slide bearing surfaces 68 extending longitudinally of the levers and forming slide bearings respectively on the levers and having slidable vertical bearing engagement with the rollers 62 to pivotally confine the levers for independent vertical oscillation thereof and to permit relative movement between the levers and these rollers horizontally and radially of these rollers, these rollers thus forming a pivotal bearing establishing a pivotal axis on which the levers are coaxially pivotally mounted and which pivotal axis is adjustable horizontally and radially thereof by adjustment of the shank 32 of the stud 31 along the slot 15 of the arm 11 as hereinbefore described.

Each of the levers 66 and 67 is also provided with spaced concentrically arcuate opposing slide bearing surfaces 69 having their axis in the region of and disposed correspondingly with the pivotal axis established by the rollers 62 and disposed in transverse relation with the bearing surfaces 68 and preferably extending across the horizontal axial plane of the rollers 62 and forming coaxial arcuate slide bearings respectively on the levers and having slidable horizontal bearing engagement with the rollers 64 radially of the levers to correspondingly independently confine the levers and to permit independent pivotal movement of the levers on the pivotal axis established by the rollers 62, the rollers 66 forming a pivotal bearing so that the levers are pivotal as well as slidable with respect to these rollers by reason of the bearing engagement of the bearing surfaces 69 therewith, it being observed that the levers are bodily adjustable horizontally and radially of the rollers 62 by adjustment of the shank 35 of the stud 34 along the slot of the arm 11 as hereinbefore described.

The rollers 62 and the bearing surfaces 68 engaged therewith form one bearing means, and the rollers 64 and the bearing surfaces 69 engaged therewith form another bearing means, and these two bearing means form a pivotal mounting for the levers 66 and 67 whereby they are independently vertically oscillable as hereininafter more fully described, the rollers 62 and 64 being mounted on the arm 11 for independent adjustment horizontally and radially of the levers and being vertically adjustable together by vertical adjustment of the arm 11 pivotally on the axis of the bore 7 for purposes hereininafter appearing.

A rotatable shaft 70 extends in the bore 7 and recess 2 and is rotatably mounted in coaxial relation therewith and accordingly is disposed on an axis parallel to the pivotal axis of the levers 66 and 67 and intermediate the ends thereof, see Figures 1 and 2, the shaft being rotatably mounted on suitable bearings, one of which is generally designated at 71 in Figure 2 and is associated with the cover plate 10 which forms a support therefor. Each of the levers 66 and 67 is provided with an intermediate opening 72 through which the shaft 70 extends, and the shaft is provided with a flange 73 adjacently spaced forwardly of the lever 66.

A series of members are mounted in succession on the shaft 70 rearwardly of the flange 73 by means of the shaft engaging through axial bores of these members, and progressing rearwardly from the flange, see Figure 2, these members consist of a bearing disk 74, a radial cam 75, a bearing disk 76, a radial cam 77, a bearing disk 78, a radial cam 79, a bearing disk 80, a lubricant confining flange 81, and a flywheel 82, which are clamped between the flange 73 and a nut 83 screwthreaded on the shaft rearwardly of the flywheel and bearing forwardly thereagainst and which are keyed to the shaft as designated at 84 in Figure 1.

The bearing disks 74 and 76 rotatably and slidably engage the lever 66 therebetween and the bearing disks 76 and 78 rotatably and slidably engage the lever 67 therebetween to provide side bearings for these levers, the cams 75 and 77 being disposed respectively within the openings 72 of the levers 66 and 67. The openings 72 of these levers are each provided with vertically spaced parallel opposing bearing surfaces 85 extending radially of the levers and horizontally and forming slide bearings which are respectively rotatably and slidably engaged on the cams 75 and 77 so that the levers are oscillated with rotation of the shaft 70 and the cams, it being observed that the engagement of these slide bearings with the cams 75 and 77 permits bodily adjustment of the levers radially and horizontally thereof as effected by corresponding adjustment of the bearing rollers 64. The cams 75 and 77 are of corresponding contour and are timed in diametrically opposite relation so that the levers 66 and 67 are oscillated in timed opposite movement phase relation with the result that the lever 67 acts as a counterbalance with reference to the lever 66 and a strip feed shuttle 86 vertically reciprocated by the lever 66, the levers 66 and 67 being preferably substantially identical with resulting substantially identical weight distribution and being coaxially pivotally mounted and the cams 75 and 77 preferably having identical lifts and being identically operative on the levers. However, additional weight may be added to the counterbalancing lever 67, preferably at the free end thereof as indicated by the dot and dash line 87 in Figure 1, to more fully counterbalance the lever 66 and feed shuttle 86.

A vertically extending strip feed guide is carried with and arranged forwardly of the frame part 1 in front of the light aperture 3 and opening 5. As shown, this feed guide is of the same construction as that described and claimed in my co-pending application for United States Letters Patent, Serial No. 762,747, filed July 22, 1947, now abandoned, for improvement in Strip feed guide and also embodies structures described and claimed in United States Letters Patent No. 2,374,486, granted April 24, 1945, on my application for Strip feed guide, and comprises as follows:

Two series of transversely spaced laterally flexible wire-like longitudinally tensioned guide members 88 and 89 extend longitudinally of the guide and are adjacently spaced facewise of the guide to facewise guide a feed perforated motion picture film strip 91 therebetween. See Figures 1 and 12. Each series of guide members comprises two widely transversely spaced pairs of adjacently transversely spaced guide members adapted to engage respective of marginal portions of the film strip, and one pair of guide members of each series spans the usual feed perforated

portion of the film strip having feed perforations 92 spaced longitudinally of the strip. Two guide rollers 93 are disposed at opposite sides of the guide and, extending longitudinally of the guide, edgewise engage the film strip therebetween for edge guiding the same. The strip 91 is thus guided for vertical longitudinal movement, and the guide is so related with the light aperture 3 that the intermediate picture record portion 94 of the strip passes the light aperture for the projection of light therethrough as an incident of the projection of pictures therefrom.

A laterally flexible wire-like bearing member 95 extends vertically and longitudinally of the feed guide and the film strip 91 guided therein, and is adjacently spaced facewise and rearwardly of the guided strip and dispose substantially opposite the feed perforated portion of the strip having the feed perforations 92. See Figures 1, 12, 13 and 14. The bearing member 95 is carried by the frame part 1 immediately in front of the front face thereof and is mounted thereon in the following manner. See Figures 4 and 5.

The lower end of the bearing member 95 is provided with a hook 96 which is engaged upwardly about a grooved stud 97 secured on the frame plate 1 and disposed a considerable distance below the opening 5, and a second stud 98 is secured on the frame plate and engages the outer side of the extremity of the hook to prevent the hook from opening when the bearing member is longitudinally tensioned. The upper end of the bearing member 95 is disposed a considerable distance above the light aperture 3 and is provided with a hook 99 projecting rearwardly into a vertical slot 101 in the forward face of the frame plate 1. A horizontally disposed lever 102 is disposed in a horizontal slot 103 in the forward face of the frame plate 1 and is pivotally mounted on the frame plate as designated at 104. A headed stud 105, secured on the frame plate 1, rearwardly engages the lever 102 intermediately thereof to retain this lever against forward movement. The free end of the lever 102 upwardly engages the hook 99 so that upward movement of this lever longitudinally tensions the bearing member 95 in co-operation with engagement of the hook 96 with the stud 97, and an eccentric stud 106 is mounted for angular movement on the frame plate 1 and engages upwardly on the intermediate portion of the lever 102 to position the lever in an upper position thereof and thus place the bearing member 95 under considerable longitudinal tension to maintain it straight and thus provide a rigid bearing despite the small diameter of the bearing member, the extremity of the hook 99 being engageable with the bottom of the slot 101 to prevent this hook from opening when the bearing member is longitudinally tensioned. The upper portion of the bearing member 95 is not used as a bearing, and a stud 107 is secured on the frame plate 1 some distance below the hook 99 and above the bearing portion of the bearing member and is provided with a diametrical groove 108 in which the bearing member is engaged to laterally stabilize the same.

The strip feed shuttle 86 is of elongated tubular form and of relatively small diameter and has its bore 109 engaged on the bearing member 95, below the stud 107 and between the spaced points along the bearing member at which the tensioning support means of the bearing member is operative thereon, for vertical reciprocating strip feed and return movement of the feed shuttle 75

longitudinally of the guided film strip 91 and for oscillatory strip perforation engaging and disengaging movement of the feed shuttle along and about the bearing member 95 which defines an axis extending longitudinally of the guided film strip and adjacently spaced facewise from the guided film strip and disposed substantially opposite the feed perforated portion of the strip and along which the feed shuttle is reciprocable and about which it is oscillable. See Figures 1 to 5 inclusive and 12, 13 and 14.

The upper longitudinal portion of the feed shuttle 86 is provided with a plurality of feed teeth 111 spaced longitudinally thereof in correspondence with the spacing of the feed perforations 92 of the film strip and extending correspondingly radially of the feed shuttle, and these feed teeth are adapted for desirable strip perforation engaging and disengaging movement with the oscillatory movement of the shuttle in an arcuate path extending predominantly edgewise of the strip, as best shown in Figure 12 in which the feed perforation engaged position of the feed teeth is shown in full lines and in which the feed perforation disengaged position of the feed teeth is shown in dot and dash lines, the shuttle and its bearing and the feed teeth of the shuttle affording a compact and light weight construction and the shuttle bearing affording adequate bearing support for the shuttle.

The lower longitudinal portion of the feed shuttle 86 is provided with a gear rack 112 extending longitudinally thereof and having the teeth thereof arcuate and disposed concentrically 35 of the shuttle bore 109 and thus concentrically of the shuttle axis, and is also provided with a gear 113 adjacently spaced below the gear rack 112 and disposed concentrically of the shuttle bore and axis. The gear rack 112 and the gear 40 113 are disposed at the opening 5, and the levers 66 and 67 being mounted for pivotal movement corresponding with the reciprocatory feed and return movement of the feed shuttle, the lever 66 is provided with a gear segment 114 meshing with 45 the gear rack 112 for reciprocating the feed shuttle with oscillation of this lever by the cam 75 which, it will be observed, is operative on this lever intermediate the pivotal axis thereof and the gear segment for oscillating this lever and consequently effecting reciprocatory feed and return movement of the feed shuttle. Oscillatory feed perforation engaging and disengaging movement of the feed shuttle is accommodated for by the teeth of the gear rack being arcuate and disposed concentrically of the shuttle axis.

An elongated rack member 115 is mounted for longitudinal reciprocation transversely of the shuttle axis and corresponding with the planes of movement of the levers 66 and 67, it being slidably mounted in a correspondingly extending groove 116 in the rear face of the transverse wall of the recess 2 and disposed below the recess 4 and shaft 70, and slidably retained in this groove by a headed screw 117 forwardly engaging the rack member, as best shown in Figure 1. The rack member 115 is provided at one end with a gear rack 118 extending longitudinally of the reciprocatory path thereof and meshing with the shuttle gear 113 for oscillating the feed shuttle 70 with reciprocation of the rack member. The other end of this rack member is disposed below the shaft 70 and is provided with an upwardly facing transverse slot 119. Reciprocatory feed and return movement of the feed shuttle along its axis is accommodated for by the shuttle gear

113 being extended longitudinally of the shuttle axis to retain its mesh with the gear rack 118 throughout the reciprocatory movement of the shuttle.

A stud 120 is frictionally engaged for angular adjustment in a bore 121 in the frame plate 1 and extending forwardly of the rear face of the transverse wall of the recess 2 in parallelism with the shaft 70 and disposed above the recess 4 and this shaft, see Figures 1 and 6. A stud 122 is mounted eccentrically on the rear end of the stud 120 for adjustment horizontally and corresponding with longitudinal movement of the rack member 115 with angular adjustment of the stud 120. A vertically extending lever 123 is provided with a bore 124 at its upper end which is pivotally engaged on the stud 122 whereby this lever is mounted for pivotal movement transversely of the reciprocatory path of the feed shuttle 86 on an axis parallel to the pivotal axis of the levers 66 and 67 and to the axis of the shaft 70 and the cams 75, 77 and 79 thereon, the axis of this shaft and these cams being parallel to the pivotal axis of the levers 66 and 67 and being disposed intermediate the pivotal axis of the levers 66 and 67 and the gear segment 114. The lower end of the lever 123 is provided with a stud 125 which is engaged in the slot 119 of the rack member 115, so that oscillation of the lever 123 effects reciprocation of the rack member 115 and consequent oscillatory feed perforation engaging and disengaging movement of the feed shuttle 86 on its axis.

The main portion of the lever 123 is provided with an opening 126 through which the shaft 70 extends and in which the cam 79 is disposed, and the bearing disks 78 and 80 rotatably and slidably engage this lever therebetween to provide side bearings therefor. The opening 126 of the lever 123 is provided with horizontally spaced parallel opposing bearing surfaces 127 extending radially of this lever and vertically and forming a slide bearing which is rotatably and slidably engaged by the cam 79 so that this lever is oscillated with rotation of the shaft 70 and this cam to effect oscillatory feed perforation engaging and disengaging movement of the feed shuttle on its axis through the rack member 115, the cams 75 and 79 being so timed as to effect intermittent feed of the film strip 91 with rotation of the shaft 70.

Figures 13 and 14 show the intermittent feed mechanism in opposite positions of the feed cycle thereof. Assuming the shaft 70 and its cams to be rotating counterclockwise in these figures, Figure 13 shows the feed shuttle 86 positioned at the upper end of its reciprocatory feed and return movement and positioned angularly in feed perforation engaged position preparatory to being actuated downwardly on its feed stroke during which the film strip 91 is fed downwardly, and Figure 14 shows the feed shuttle positioned at the lower end of its reciprocatory strip feed and return movement and positioned angularly in feed perforation disengaged position preparatory to being actuated upwardly on its return stroke during which the film strip remains stationary. It is to be observed that in Figure 13, the feed shuttle actuating lever 68 is at the upper end of its stroke, while the counterbalancing lever 67 is at the lower end of its stroke, and that in Figure 14 the lever 68 is at the lower end of its stroke, while the lever 67 is at the upper end of its stroke, which illustrates the counterbalancing action of the lever 67.

Angular adjustment of the stud 120 effects adjustment of the pivotal axis of the lever 123 horizontally and corresponding with the plane of movement of this lever to adjust the oscillating stroking range of the feed shuttle with resulting adjustment of the feed perforation engaged and disengaged positions of the feed teeth of the feed shuttle, and is an assembly adjustment.

The pivotal axis established by the rollers 62 for the levers 66 and 67 is disposed in the region of the axis of the gear segment 114 and on the line, designated at 128 in Figure 13, extending radially of the gear segment and normal to the reciprocatory path of the feed shuttle 86, the straight slide bearings on the levers 66 and 67 formed by the bearing surfaces 68 extend longitudinally of the radius of the gear segment which coincides with the line 128 when these levers are midway of their strokes, and the arcuate slide bearings on the levers 66 and 67 formed by the bearing surfaces 69 are disposed concentrically of the gear segment 114.

The bearing surfaces 68 on the levers 66 and 67 have bearing engagement with the rollers 62 longitudinally of the reciprocatory film strip feed and return path of the feed shuttle 86 to correspondingly pivotally confine these levers on the pivotal axis established by the rollers 62 and to permit relative movement between these levers and these pivotal axis establishing rollers longitudinally of the radius of the gear segment 114 which coincides with the line 128 when these levers are midway of their strokes. The bearing surfaces 69 on the levers 66 and 67 have bearing engagement with the rollers 64 longitudinally of the line 128 to correspondingly confine these levers and to permit pivotal movement of these levers on the pivotal axis established by the rollers 62, and the cooperating bearing surfaces 69 and rollers 64 are operative in cooperation with the cooperating bearing surfaces 66 and rollers 62 to effect oscillation of the gear segment 114 of the lever 66 and the corresponding portion of the lever 67 substantially on the axis of the gear segment throughout a range of adjustment of the rollers 62 and the pivotal axis established thereby along the line 128 and in the region of the gear segment axis so that a substantially uniform mesh of the gear segment with the gear rack 112 of the feed shuttle is maintained throughout the oscillation of the lever 66 despite the adjustment of the rollers 62 along the line 128, the said adjustment of the rollers 62 being effected by adjustment of the shank 32 of the stud 31 along the slot 15 of the arm 11 as hereinbefore described. Observing that the cooperating bearing surfaces 69 and rollers 64 position the levers 66 and 67 longitudinally of the line 128, this adjustment of the rollers 62 effects adjustment of the pivotal axis of these levers relative thereto and along the line 128 so that the extent of the stroke of the gear segment is correspondingly adjusted with corresponding adjustment of the extent of the reciprocatory strip feed and return movement of the feed shuttle 86 to conform with the spacing of the feed perforations 92 of the film strip 91 and so to accommodate for shrinkage or expansion of the strip, this adjustment of the rollers 62 being preferably an operating adjustment effected by rotational adjustment of the shaft 54 which is operatively connected with the stud 31 to angularly adjust the same as hereinbefore described.

Figure 10 illustrates the adjustment of the rollers 62 in which their axis is coincident with that of the gear segment 114 and the bearing surfaces

69, the corresponding extent of the stroke of the gear segment and of the reciprocatory feed and return movement of the feed shuttle 86 being illustrated by the bracket 129. In this adjustment of the rollers 62, the bearing surfaces 68 merely pivot on the axis of these rollers and do not slide on the rollers and the bearing surfaces 69 merely slide on the rollers 64 and do not pivot on the axis of these rollers.

Figure 11 illustrates adjustments of the rollers 62 in which their axis is displaced from the axis of the gear segment 114 and the bearing surfaces 69 in both directions along the line 128, the position of the rollers 62 spaced from the axis of the gear segment in the direction away from the gear segment being shown in full lines and designated at 130 and the position of the rollers 62 spaced from the axis of the gear segment in the direction toward the gear segment being shown in interrupted lines and designated at 131. In the position 130 in Figure 11 of the rollers 62, the corresponding extent of the stroke of the gear segment 114 and the reciprocatory feed and return movement of the feed shuttle 86 is illustrated by the bracket 132, the extent of which is less than the extent of the stroke of the gear segment and reciprocatory feed and return movement of the feed shuttle designated at 129 in Figure 10 and in the position 131 in Figure 11 of the rollers 62, the corresponding extent of the stroke of the gear segment and the reciprocatory feed and return movement of the feed shuttle is illustrated by the bracket 133, the extent of which is greater than the extent of the stroke of the gear segment and reciprocatory feed and return movement of the feed shuttle designated at 129 in Figure 10. In either of the positions 130 and 131 of the rollers 62 shown in Figure 11, the bearing surfaces 68 both pivot on the axis of these rollers and slide on these rollers and the bearing surfaces 69 both slide on the rollers 64 and pivot on the axis of these latter rollers.

Adjustment of the rollers 64 longitudinally of the line 128, by adjustment of the shank 35 of the stud 34 along the slot 15 of the arm 11, as hereinbefore described, effects bodily adjustment of the levers 66 and 67 along this line for the purpose of adjusting the mesh of the gear segment 114 of the lever 66 with the gear rack 112 of the feed shuttle and is an assembly adjustment.

The rollers 62 and 64 are adjustable longitudinally of the reciprocatory feed and return movement of the feed shuttle 86 by pivotal adjustment of the arm 11 on the axis of the shaft 70, which adjustment effects corresponding adjustment of the pivotal axis of the levers 66 and 67 and corresponding adjustment of the line 128 and the stroking range of the levers 66 and 67 and the feed shuttle for "framing" the picture frames of the film strip 91 with the light aperture 3. In Figure 1, the arm 11 is shown in an intermediate position of its adjustment, and in Figure 9 the lower extreme of adjustment of this arm is shown in full lines and the upper extreme of adjustment of this arm is shown in dot and dash lines, this adjustment being preferably an operating adjustment.

It will be observed that the hereinbefore described adjustments of the rollers 62 and 64 are correspondingly effective on the levers 66 and 67 so that these adjustments do not alter the counterbalancing action of the lever 67.

The flywheel 82 is disposed rearwardly within the enclosure formed by the recess 2 and cover plate 10, and an annular light shutter 134 also

disposed within this enclosure is secured on the flywheel 82 in concentric relation therewith, as designated at 135, and has its peripheral portion 136 offset forwardly as designated at 137 to lie closely adjacent the rear face of the transverse wall of the recess 2. See Figures 1 and 2. The peripheral portion 136 of the shutter sweeps across the light aperture 3 and is provided with a segmental light opening 138, see Figure 1, to intermittently pass light through the light aperture 3 in timed relation with intermittent feed of the film strip 91 as is usual in motion picture machines.

The periphery of the flywheel 82 is provided with a facing 139 of non-metallic friction material and belt 141 is frictionally engaged about the facing for driving the shaft 70 and the parts mounted thereon from a motor not shown.

As before described, the shaft 70 is rotatably mounted on suitable bearings, one of which is generally designated at 71 in Figure 2 and is associated with the cover plate 10 which forms a support therefor. The bearings of this shaft are similar to those described and claimed in my co-pending application for United States Letters Patent, Serial No. 556,175, filed September 28, 1944, for improvement in Bearing, and upon which Patent No. 2,455,489 has issued.

Referring to Figure 2, the central portion of the cover plate 10 is offset rearwardly and forms a relatively large forwardly facing circular recess 142 disposed coaxially of the bore 7 and into which the rearward end portion of the shaft 70 projects, and a collar 143, through which the shaft projects, is screwthreaded rearwardly into the recess 142 and clamps the periphery of a circularly fluted diaphragm 144 against a forwardly facing shoulder 145 of the recess 142, the diaphragm being disposed coaxially of the shaft 70 and being provided with an axial aperture 146 in which a bearing member 147 is suitably secured in coaxial relation with the bore 7. A concentrically bored bushing 148 is screwthreaded into a bore 149 through the cover plate 10 and is disposed coaxially of the bore 7, and a lock nut 151, screwthreaded on this bushing and engageable against the cover plate, serves to secure this bushing in axially adjusted position. An adjustment screw 152 is screwthreaded into the bore of the bushing 148, and a lock nut 153, screwthreaded on this screw, and engageable against this bushing, serves to secure this screw in axially adjusted position. A helical compression spring 154 is operative between the screw 152 and the bearing member 147 to yieldably urge this bearing member forwardly, the tension of this spring being adjustable by axial adjustment of the screw 152 and the diaphragm 144, permitting axial movement of the bearing member while maintaining it in coaxial relation with the bore 7.

The bearing member 147 is provided with a forwardly facing concentric bearing surface 156 of concave part spherical character, and the rear end of the shaft 70 is provided with a rearwardly facing concentric bearing surface 157 of concave part spherical character which opposes the bearing surface 156 axially of the rotational axis of the shaft. A bearing member 158 of convex spherical character, such as a bearing ball, is disposed between and has opposite bearing engagement with the bearing surfaces 156 and 157 to rotatably support the rear end of the shaft. A second bearing, not shown and essentially the same as the bearing 71, rotatably supports the forward end of the shaft 70 and cooperates with

the bearing 71 in axially opposing relation therewith to rotatably support the shaft, the bearing member of the second bearing which corresponds with the bearing member 147, being rigidly supported axially. The spring 154 serves to preload the bearings of the shaft 70, the preloading pressure being adjustable by adjustment of the screw 152.

Constant lubrication of the bearings of the shaft 70 is provided in accordance with said Patent No. 2,455,489, and involves an axial lubricant bore 159 through the shaft 70, a lubricant bore 161 extending diametrically through the ball bearing member 158, and a fluted pin 162 engaged in the bore 161 and adapted to permit the passage of lubricant thereby and loosely engaged, for example, in the bore 159 to permit limited angular movement of the bearing member 158 transversely of the rotational axis of the shaft within a range maintaining communication of these bores, the ball bearing member of the aforementioned second bearing of the shaft being also provided with a diametrical lubricant bore and a fluted limiting pin engaged therein and functioning in the same manner as the pin 162. Lubricant under pressure passes rearwardly through the diametrical bore of the ball bearing member of the aforementioned second shaft bearing, the bore 159 of the shaft 70 and the bore 161 of the ball bearing member 158 primarily for lubricating the bearings of the shaft.

The collar 143 is provided with an internal flange 163 disposed forwardly of the rear end of the shaft 70, and this flange and the diaphragm 144 form an annular lubricant collecting enclosure 164 surrounding the bearing 71 for collecting lubricant seeping therefrom, an oil throw flange 165, on the rear portion of the shaft and surrounded by this enclosure, serving to throw lubricant seeping from the bearing 71 into this enclosure. The rearward end of the collar 143 is provided with radial slots 166 spaced angularly thereabout which communicate with a circular groove 167 of the recess 142, and lubricant collected in the enclosure 164 passes through the lowermost of the slots 166 into the groove 167 from which the lubricant is drained through a suitable duct not shown.

The transverse wall of the recess 2 is provided with a circular rearward projection 168 of relatively large diameter, and this projection is disposed concentrically of the bore 1 and is of greater diameter than the extent of the recess 4. The lubricant confining flange 51, which is also of relatively large diameter, is disposed immediately rearward of the projection 168 and rearwardly overlies the recess 4 and the shuttle actuating mechanism. A circular concentrically bored cover disk 169, through the bore of which the shaft 71 extends, is disposed immediately forward of the flange 51 and is secured on the projection 168 by means of a circumferential flange 171 of the disk being screw threaded on the periphery of the projection 168, an annular spacing washer 172 being interposed between the projection and the disk to rearwardly space the disk from the projection and thus provide clearance for the flange 51 therebetween. Lubricant escaping from the shuttle actuating mechanism is thus directed into the space between the projection 168 and disk 169 and is drained from the lower portion of this space by a suitable duct 173, shown in Figures 1 and 8.

A frame part 174, see Figure 1, is suitably secured on the forward surface of the transverse

wall of the recess 2 in front of the opening 5 and so encloses this opening. This frame part is provided with a rearwardly facing vertical groove 175 forwardly enclosing the lower portion of the feed shuttle 26. The upper portion of the frame part 174 is provided with a relatively large opening 176 which is intersected by the groove 175 at the intermediate portion of the feed shuttle between the upper feed tooth portion thereof and the lower rack and gear portion thereof. Suitable packing material 177 is disposed in the opening 176 and surrounds the said intermediate portion of the shuttle and slidably engages the same to prevent lubricant from working upwardly on the shuttle to the upper feed tooth portion thereof where it might otherwise contact the film strip 91 in the feed guide.

While I have thus described my invention, I do not wish to be limited to the precise details described, as changes may be readily made without departing from the spirit of my invention, but having thus described my invention, I claim as new and desire to secure by Letters Patent the following:

1. In an intermittent strip feed mechanism, the combination of toothed strip feed means, a lever mounted for pivotal movement and connected with said feed means for effecting reciprocatory strip feed and return movement of said feed means with oscillation of said lever, means for oscillating said lever, and the pivotal mounting of said lever comprising a first bearing means establishing a pivotal axis spaced transversely from the reciprocatory path of said feed means and operative on said lever longitudinally of said reciprocatory path to correspondingly pivotally confine said lever and to permit relative movement between said lever and said pivotal axis radially of said lever and transversely of said reciprocatory path and a second bearing means operative on said lever radially of said lever and transversely of said reciprocatory path to correspondingly confine said lever and to permit pivotal movement of said lever on said pivotal axis and operative in cooperation with said first bearing means to determine the character of reciprocation of the feed means connected portion of said lever.

2. In an intermittent strip feed mechanism, the combination of toothed strip feed means, a lever mounted for pivotal movement and connected with said feed means for effecting reciprocatory strip feed and return movement of said feed means with oscillation of said lever, means for oscillating said lever, and the pivotal mounting of said lever comprising a pivotal first bearing member establishing a pivotal axis spaced transversely from the reciprocatory path of said feed means, a lineal second bearing member on said lever and extending radially of said lever and transversely of said reciprocatory path and having bearing engagement with said first bearing member longitudinally of said reciprocatory path to correspondingly confine said lever and to permit relative movement between said lever and first bearing member radially of said lever and transversely of said reciprocatory path, a third bearing member on said lever, and a fourth bearing member having bearing engagement with said third bearing member radially of said lever and transversely of said reciprocatory path to correspondingly confine said lever and to permit pivotal movement of said lever on said pivotal axis and at least one of said third and fourth bearing members being lineal and extending lineally of said reciprocatory path, said bearing members cooper-

ating to determine the character of reciprocation of the feed means connected portion of said lever.

3. In an intermittent strip feed mechanism, the combination of toothed strip feed means, a lever mounted for pivotal movement and connected with said feed means for effecting reciprocatory strip feed and return movement of said feed means with oscillation of said lever, means for oscillating said lever, and the pivotal mounting of said lever comprising a first bearing means establishing a pivotal axis spaced transversely from the reciprocatory path of said feed means and operative on said lever longitudinally of said reciprocatory path to correspondingly pivotally confine said lever and to permit relative movement between said lever and said pivotal axis radially of said lever and transversely of said reciprocatory path and including adjustable means operative to adjust said pivotal axis radially of said lever and transversely of said reciprocatory path and a second bearing means operative on said lever radially of said lever and transversely of said reciprocatory path to correspondingly confine said lever and to permit pivotal movement of said lever on said pivotal axis and operative in cooperation with said first bearing means to determine the character of reciprocation of the feed means connected portion of said lever.

4. In an intermittent strip feed mechanism, the combination of toothed strip feed means, a lever mounted for pivotal movement and connected with said feed means for effecting reciprocatory strip feed and return movement of said feed means with oscillation of said lever, means for oscillating said lever, and the pivotal mounting of said lever comprising a pivotal first bearing member establishing a pivotal axis spaced transversely from the reciprocatory path of said feed means, a lineal second bearing member on said lever and extending radially of said lever and transversely of said reciprocatory path and having bearing engagement with said first bearing member longitudinally of said reciprocatory path to correspondingly confine said lever and to permit relative movement between said lever and first bearing member radially of said lever and transversely of said reciprocatory path, a third bearing member on said lever, and a fourth bearing member having bearing engagement with said third bearing member radially of said lever and transversely of said reciprocatory path to correspondingly confine said lever and to permit pivotal movement of said lever on said pivotal axis and at least one of said third and fourth bearing members being lineal and extending lineally of said reciprocatory path, said bearing members cooperating to determine the character of reciprocation of the feed means connected portion of said lever.

5. In an intermittent strip feed mechanism, the combination of a toothed strip feed shuttle mounted for reciprocatory strip feed and return movement, a lever mounted for pivotal movement corresponding with the reciprocatory path of said shuttle, an operative connection between said shuttle and lever for reciprocating said shuttle with oscillation of said lever and including a segment on said lever and having rolling relation with said shuttle, means for oscillating said lever, and the pivotal mounting of said lever comprising a first bearing means establishing a pivotal axis in the region of the axis of said segment and on the line extending radially of said segment and normal to said reciprocatory path and operative on said lever longitudinally of said reciprocatory path to

correspondingly pivotally confine said lever and to permit relative movement between said lever and said pivotal axis longitudinally of the radius of said segment which coincides with said line when said lever is midway of its stroke and including adjustable means operative to adjust said pivotal axis along said line and a second bearing means operative on said lever longitudinally of said line to correspondingly confine the same and to permit pivotal movement of said lever on said pivotal axis and operative in cooperation with said first bearing means to effect oscillation of said segment substantially on the axis of said segment throughout a range of said adjustment of said pivotal axis.

6. In an intermittent strip feed mechanism, the combination of a toothed strip feed shuttle mounted for reciprocatory strip feed and return movement, a lever mounted for pivotal movement corresponding with the reciprocatory path of said shuttle, an operative connection between said shuttle and lever for reciprocating said shuttle with oscillation of said lever and including a segment on said lever and having rolling relation with said shuttle, means for oscillating said lever, and the pivotal mounting of said lever comprising a pivotal first bearing member establishing a pivotal axis in the region of the axis of said segment and on the line extending radially of said segment and normal to said reciprocatory path and mounted for adjustment along said line, a lineal second bearing member on said lever and extending longitudinally of the radius of said segment which coincides with said line when said lever is midway of its stroke and having bearing engagement with said first bearing member longitudinally of the said reciprocatory path to correspondingly pivotally confine said lever and to permit relative movement between said lever and said first bearing member longitudinally of said radius, a lineal third bearing member on said lever and extending the plane of movement of said lever in transverse relation with said second bearing member, and a fourth bearing member having bearing engagement with said third bearing member longitudinally of said line to correspondingly confine said lever and to permit pivotal movement of said lever on said pivotal axis, said bearing members being operative to effect oscillation of said segment substantially on the axis of said segment throughout a range of said adjustment of said first bearing member.

7. In an intermittent strip feed mechanism, the combination of a toothed strip feed shuttle mounted for reciprocatory strip feed and return movement, a lever mounted for pivotal movement corresponding with the reciprocatory path of said shuttle, an operative connection between said shuttle and lever for reciprocating said shuttle with oscillation of said lever and including a segment on said lever and having rolling relation with said shuttle, means for oscillating said lever, and the pivotal mounting of said lever comprising a pivotal first bearing member establishing a pivotal axis in the region of the axis of said segment and on the line extending radially of said segment and normal to said reciprocatory path and mounted for adjustment along said line, a straight lineal second bearing member on said lever and extending longitudinally of the radius of said segment which coincides with said line when said lever is midway of its stroke and having bearing engagement with said first bearing member longitudinally of said reciprocatory path to

correspondingly pivotally confine said lever and to permit relative movement between said lever and said first bearing member longitudinally of said radius, an arcuate lineal third bearing member on said lever and disposed concentrically of said segment and in transverse relation with said second bearing member, and a pivotal fourth bearing member having bearing engagement with said third bearing member longitudinally of said line to correspondingly confine said lever and to permit pivotal movement of said lever on said pivotal axis and mounted for adjustment longitudinally of said line to correspondingly adjust said lever, said bearing members being operative to effect oscillation of said segment substantially on the axis of said segment throughout a range of said adjustment of said first bearing member.

8. In an intermittent strip feed mechanism, the combination of a toothed strip feed shuttle mounted for reciprocatory strip feed and return movement, a lever mounted for pivotal movement corresponding with the reciprocatory path of said shuttle, an operative connection between said shuttle and lever for reciprocating said shuttle with oscillation of said lever and including a segment on said lever and having rolling relation with said shuttle, means for oscillating said shuttle, and the pivotal mounting of said lever comprising a first bearing means establishing a pivotal axis in the region of the axis of said segment and on the line extending radially of said segment and normal to said reciprocatory path and operative on said lever longitudinally of said reciprocatory path to correspondingly pivotally confine said lever and to permit relative movement between said lever and said pivotal axis longitudinally of the radius of said segment which coincides with said line when said lever is midway of its stroke and including adjustable means operative to adjust said pivotal axis along said line and a second bearing means operative on said lever longitudinally of said line to correspondingly confine the same and to permit pivotal movement of said lever on said pivotal axis and operative in cooperation with said first bearing means to effect oscillation of said segment substantially on the axis of said segment throughout a range of said adjustment of said pivotal axis and including adjustable means operative to adjust said lever longitudinally of said line.

9. In an intermittent strip feed mechanism, the combination of a toothed strip feed shuttle mounted for reciprocatory strip feed and return movement, a lever mounted for pivotal movement corresponding with the reciprocatory path of said shuttle, an operative connection between said shuttle and lever for reciprocating said shuttle with oscillation of said lever and including a segment on said lever and having rolling relation with said shuttle, and the pivotal mounting of said lever comprising a pivotal first bearing member establishing a pivotal axis in the region of the axis of said segment and on the line extending radially of said segment and normal to said reciprocatory path and mounted for adjustment along said line, a lineal second bearing member on said lever and extending longitudinally of the radius of said segment which coincides with said line when said lever is midway of its stroke and having bearing engagement with said first bearing member longitudinally of said reciprocatory path to correspondingly pivotally confine said lever and to permit relative movement between said lever and said first bearing member longitudinally of said radius, a lineal third bearing member on said lever and extending in the plane of movement of said lever in trans-

verse relation with said second bearing member, and a fourth bearing member having bearing engagement with said third bearing member longitudinally of said line to correspondingly confine said lever and to permit pivotal movement of said lever on said pivotal axis and mounted for adjustment longitudinally of said line to correspondingly adjust said lever, said bearing members being operative to effect oscillation of said segment substantially on the axis of said segment throughout a range of said adjustment of said first bearing member.

10. In an intermittent strip feed mechanism, the combination recited in claim 5 and further characterized in combination in that said first bearing means includes a second adjustable means operative to adjust said pivotal axis longitudinally of said reciprocatory path.

11. In an intermittent strip feed mechanism, the combination recited in claim 6 and further including in combination a mounting member mounted for adjustment longitudinally of said reciprocatory path and upon which said first bearing member is mounted for said adjustment thereof.

12. In an intermittent strip feed mechanism, the combination recited in claim 9 and further including in combination a mounting member mounted for adjustment longitudinally of said reciprocatory path and upon which said first and fourth bearing members are mounted for said adjustments thereof.

13. In an intermittent strip feed mechanism, the combination recited in claim 6 and further characterized in that said lever oscillating means comprises a rotatory member operative on said lever and disposed on an axis parallel to and spaced from said pivotal axis longitudinally of said line, and further including in combination a mounting member mounted for pivotal adjustment on the axis of said rotatory member and upon which said first bearing member is mounted for said adjustment thereof.

14. In an intermittent strip feed mechanism, the combination recited in claim 7 and further characterized in that said lever oscillating means comprises a rotatory member operative on said lever and disposed on an axis parallel to and spaced from said pivotal axis longitudinally of said line, and further including in combination a mounting member mounted for pivotal adjustment on the axis of said rotatory member and upon which said first bearing member is mounted for said adjustment thereof and upon which said fourth bearing member is also mounted.

15. In an intermittent strip feed mechanism, the combination recited in claim 9 and further characterized in that said lever oscillating means comprises a rotatory member operative on said lever and disposed on an axis parallel to and spaced from said pivotal axis longitudinally of said line, and further including in combination a mounting member mounted for pivotal adjustment on the axis of said rotatory member and upon which said first and fourth bearing members are mounted for said adjustments thereof.

16. In an intermittent strip feed mechanism, the combination of a toothed strip feed shuttle mounted for reciprocatory strip feed and return movement along and for oscillating strip perforation engaging and disengaging movement about an axis extending longitudinally of a guided strip, a pair of levers substantially coaxially pivotally mounted for independent oscillation corresponding with the reciprocatory path of

said shuttle and extending correspondingly from their pivotal axis in overlying relation, an operative connection between said shuttle and a first of said levers for reciprocating said shuttle with oscillation of this lever and adapted to permit oscillation of said shuttle about said first mentioned axis, a shuttle oscillating member mounted for reciprocation transversely of said reciprocatory path and corresponding with the planes of movement of said levers and operatively connected with said shuttle for oscillating the same with reciprocation of said shuttle oscillating member, and three angularly fixed radial cams mounted for rotation on an axis parallel to the axis of said levers and two of said cams being respectively operative on said levers to oscillate the same in timed opposite movement phase relation whereby the second of said levers acts as a counterbalance and the third of said cams being operative on said shuttle oscillating member to oscillate said shuttle in timed relation with reciprocation thereof to intermittently feed the strip.

17. In an intermittent strip feed mechanism, the combination of a toothed strip feed shuttle mounted for reciprocatory strip feed and return movement along and for oscillating strip perforation engaging and disengaging movement about an axis extending longitudinally of a guided strip and said shuttle being provided with a gear rack extending longitudinally of said axis and having the teeth thereof arcuate and disposed concentrically of said axis and further provided with a gear disposed concentrically of said axis, a pair of levers coaxially pivotally mounted for independent movement corresponding with the reciprocatory path of said shuttle and extending correspondingly from their pivotal axis in overlying relation, a first of said levers being provided with a gear segment meshing with said rack for reciprocating said shuttle with oscillation of this lever, a rack member mounted for reciprocation transversely of said shuttle axis and corresponding with the planes of movement of said levers and provided with a gear rack extending longitudinally of the reciprocatory path thereof and meshing with said shuttle gear for oscillating said shuttle with reciprocation of said rack member, a third lever mounted for pivotal movement transversely of the reciprocatory path of said shuttle on an axis parallel to the pivotal axis of said pair of levers and disposed intermediate this latter axis and said gear segment and operative on said rack member to reciprocate the same with oscillation thereof, and three angularly fixed radial cams mounted for rotation on an axis parallel to the pivotal axes of said three levers and disposed intermediate the pivotal axes of said pair of levers and said gear segment and two of said cams being respectively operative on said pair of levers to oscillate the same in timed opposite movement phase relation whereby the second of said levers acts as a counterbalance and the third of said cams being operative on said third lever to oscillate said shuttle in timed relation with reciprocation thereof to intermittently feed the strip.

18. In an intermittent strip feed mechanism, the combination of toothed strip feed means, a pair of levers substantially coaxially pivotally mounted for independent pivotal movement and extending correspondingly from their pivotal axis in overlying relation and a first of said levers being connected with said feed means for effecting reciprocatory strip feed and return movement of said feed means with oscillation of this

lever, means for oscillating said levers in timed opposite movement phase relation whereby the second of said levers acts as a counterbalance, and the pivotal mounting of said levers comprising a first bearing means establishing a pivotal axis spaced transversely from the reciprocatory path of said feed means and operative on said levers longitudinally of said reciprocatory path to correspondingly pivotally confine said levers and to permit relative movement between said levers and said pivotal axis radially of said levers and transversely of said reciprocatory path and including adjustable means operative to adjust said pivotal axis radially of said levers and transversely of said reciprocatory path and a second bearing means operative on said levers radially of said levers and transversely of said reciprocatory path to correspondingly confine said levers and to permit pivotal movement of said levers on said pivotal axis and operative in cooperation with said first bearing means to determine the character of a reciprocation of the feed means connected portion of said lever.

19. In an intermittent strip feed mechanism, the combination of a toothed strip feed shuttle mounted for reciprocatory strip feed and return movement, a pair of levers substantially coaxially pivotally mounted for independent oscillation corresponding with the reciprocatory path of said shuttle and extending correspondingly from their pivotal axis in overlying relation, an operative connection between said shuttle and a first of said levers for reciprocating said shuttle with oscillation of this lever and including a segment on this lever and having rolling relation with said shuttle, means for oscillating said levers in timed opposite movement phase relation whereby the second of said levers acts as a counterbalance, and the pivotal mounting of said levers comprising a first bearing means establishing a pivotal axis in the region of the axis of said segment and on the line extending radially of said segment and normal to said reciprocatory path and operative on said levers longitudinally of said reciprocatory path to correspondingly pivotally confine said levers and to permit relative movement between said levers and said pivotal axis longitudinally of the radius of said segment which coincides with said line when said levers are midway of their strokes and including adjustable means operative to adjust said pivotal axis along said line and a second bearing means operative on said levers longitudinally of said line to correspondingly confine the same and to permit pivotal movement of said levers on said pivotal axis and operative in cooperation with said first bearing means to effect oscillation of said segment and the corresponding portion of said second lever substantially on the axis of said segment throughout a range of said adjustment of said pivotal axis.

20. In an intermittent strip feed mechanism, the combination recited in claim 19 and further characterized in combination in that said first bearing means includes a second adjustable means operative to adjust said pivotal axis longitudinally of said reciprocatory path.

21. In an intermittent strip feed mechanism, the combination recited in claim 19 and further characterized in combination in that said second bearing means includes an adjustable means operative to correspondingly adjust said levers longitudinally of said line.

22. In an intermittent strip feed mechanism, the combination recited in claim 19 and further

characterized in combination in that said first bearing means includes a second adjustable means operative to adjust said pivotal axis longitudinally of said reciprocatory path and that said second bearing means includes adjustable means operative to correspondingly adjust said levers longitudinally of said line.

23. In an intermittent strip feed mechanism, the combination of a toothed strip feed shuttle mounted for reciprocating strip feed and return movement along and for oscillating strip perforation engaging and disengaging movement about an axis extending longitudinally of a guided strip and said shuttle being provided with a gear rack extending longitudinally of said axis and having the teeth thereof arcuate and disposed concentrically of said axis, a lever mounted for pivotal movement corresponding with the reciprocatory path of said shuttle and provided with a gear segment meshing with said rack for reciprocating said shuttle with oscillation of said rack, and means for oscillating said lever and shuttle in timed relation to intermittently feed the strip.

24. In an intermittent strip feed mechanism, the combination of a toothed strip feed shuttle mounted for reciprocating strip feed and return movement along and for oscillating strip perforation engaging and disengaging movement about an axis extending longitudinally of a guided strip and said shuttle being provided with a gear rack extending longitudinally of said axis and having the teeth thereof arcuate and disposed concentrically of said axis and further provided with a gear disposed concentrically of said axis, a lever mounted for pivotal movement corresponding with the reciprocatory path of said shuttle and provided with a gear segment meshing with said rack for reciprocating said shuttle with oscillation of said lever, a rack member mounted for reciprocation transversely of said axis and provided with a gear rack extending longitudinally of the reciprocatory path thereof and meshing with said shuttle gear for oscillating said shuttle with reciprocation of said rack member, and means for oscillating said lever and reciprocating said rack member in timed relation to intermittently feed the strip.

25. In an intermittent strip feed mechanism, the combination of a toothed strip feed shuttle mounted for reciprocating strip feed and return movement along and for oscillating strip perforation engaging and disengaging movement about an axis extending longitudinally of a guided strip, said shuttle being provided with a gear rack extending longitudinally of said axis and having the teeth thereof arcuate and disposed concentrically of said axis and further provided with a gear disposed concentrically of said axis, a lever mounted for pivotal movement corresponding with the reciprocatory path of said shuttle and provided with a gear segment meshing with said rack for reciprocating said shuttle with oscillation of said lever, a rack member mounted for reciprocation transversely of said axis and corresponding with the plane of movement of said lever and provided with a gear rack extending longitudinally of the reciprocatory path thereof and meshing with said shuttle gear for oscillating said shuttle with reciprocation of said rack member, a second lever mounted for pivotal movement transversely of the reciprocatory path of said shuttle on an axis parallel to the pivotal axis of said first mentioned lever and operative on said rack member to reciprocate the same with oscillation thereof, and two angularly fixed co-

axial radial cams mounted for rotation on an axis parallel to the axes of said levers and respectively operative on said levers to oscillate the same in timed relation to intermittently feed the strip.

5 26. In an intermittent strip feed mechanism, the combination of a strip feed shuttle mounted for reciprocatory strip feed and return movement along and for oscillatory strip perforation engaging and disengaging movement about an axis extending longitudinally of a guided strip and adjacently spaced facewise from the strip and disposed substantially opposite a feed perforated portion of the strip, said shuttle being provided with a feed tooth extending radially of said axis and adapted for strip perforation engaging and disengaging movement with said oscillatory movement of said shuttle in an arcuate path extending predominately edgewise of the strip, and means for reciprocating and oscillating said shuttle along and about said axis in timed relation to intermittently feed the strip.

20 27. In an intermittent strip feed mechanism, the combination of an elongated feed shuttle extending longitudinally of a guided strip and adjacently spaced facewise from the strip and disposed substantially opposite a feed perforated portion of the strip and mounted for reciprocatory strip feed and return movement along and for oscillatory strip perforation engaging and disengaging movement about a correspondingly extending and disposed axis, one longitudinal portion of said shuttle being provided with a plurality of feed teeth spaced longitudinally and extending 25 correspondingly radially thereof and adapted for strip perforation engaging and disengaging movement with said oscillatory movement of said shuttle in an arcuate path extending predominately edgewise of the strip, and means operative on 30 said shuttle in spaced relation with said feed teeth longitudinally of said shuttle for reciprocating and oscillating said shuttle along and about said axis in timed relation to intermittently feed the strip.

40 28. In an intermittent strip feed mechanism, the combination of a laterally flexible wire-like bearing member extending longitudinally of a guided strip, tensioning support means operative on said bearing member at spaced points therealong to longitudinally tension the same, a toothed feed shuttle slidably mounted on said bearing member between said spaced points for reciprocatory strip feed and return movement, and means for reciprocating said shuttle along 45 said bearing member.

29. In an intermittent strip feed mechanism, the combination of a laterally flexible wire-like bearing member extending longitudinally of a guided strip, tensioning support means operative 50 on said bearing member at spaced points therealong to longitudinally tension the same, a toothed feed shuttle provided with a bore engaged on said bearing member between said spaced points for reciprocatory strip feed and return movement and oscillatory strip perforation engaging and disengaging movement of said shuttle along and about said bearing member, and means for reciprocating and oscillating said shuttle along and about said bearing member to intermittently feed the strip.

60 30. In an intermittent strip feed mechanism, the combination of a laterally flexible wire-like bearing member extending longitudinally of a guided strip, tensioning support means operative 65 on said bearing member at spaced points there-

along to longitudinally tension the same, a toothed elongated tubular feed shuttle having its bore engaged on said bearing member between said spaced points for reciprocatory strip feed and return movement and oscillatory strip perforation engaging and disengaging movement of said shuttle along and about said bearing member, and means for reciprocating and oscillating said shuttle along and about said bearing member to intermittently feed the strip.

31. In an intermittent strip feed mechanism, the combination of a laterally flexible wire-like bearing member extending longitudinally of a guided strip and adjacently spaced facewise of the strip and disposed substantially opposite a feed perforated portion of the strip, tensioning support means operative on said bearing member at spaced points therealong to longitudinally tension the same, an elongated tubular feed shuttle having its bore engaged on said bearing member between said spaced points for reciprocatory strip feed and return movement and oscillatory strip perforation engaging and disengaging movement of said shuttle along and about said bearing member, said shuttle being provided with a feed tooth extending radially of said bore and adapted for strip perforation engaging and disengaging movement with said oscillatory movement of said shuttle in an arcuate path extending predominately edgewise of the strip, and means for reciprocating and oscillating said shuttle along and about said bearing member in timed relation to intermittently feed the strip.

32. In an intermittent strip feed mechanism, the combination of a laterally flexible wire-like bearing member extending longitudinally of a guided strip and adjacently spaced facewise of the strip and disposed substantially opposite a feed perforated portion of the strip, tensioning support means operative on said bearing member at spaced points therealong to longitudinally tension the same, an elongated tubular feed shuttle having its bore engaged on said bearing member between said spaced points for reciprocatory strip feed and return movement and oscillatory strip perforation engaging and disengaging movement of said shuttle along and about said bearing member, one longitudinal portion of said shuttle being provided with a plurality of feed teeth spaced longitudinally and extending correspondingly radially thereof and adapted for strip perforation engaging and disengaging movement with said oscillatory movement of said shuttle in an arcuate path extending predominately edgewise of the strip, another longitudinal portion of said shuttle being provided with a gear rack extending longitudinally thereof and having the teeth thereof

arcuate and disposed concentrically of said shuttle bore and further provided with a gear disposed concentrically of said shuttle bore, a lever mounted for pivotal movement corresponding with the reciprocatory path of said shuttle and provided with a gear segment meshing with said rack for reciprocating said shuttle with oscillation of said lever, a rack member mounted for reciprocation transversely of said shuttle bore and provided with a gear rack extending longitudinally of the reciprocatory path thereof and meshing with said shuttle gear for oscillating said shuttle with reciprocation of said rack member, and means for oscillating said lever and reciprocating said rack member in timed relation to intermittently feed the strip.

33. In an intermittent strip feed mechanism, the combination of a laterally flexible wire-like vertically disposed bearing member extending longitudinally of a vertically guided strip and adjacently spaced facewise of the strip and disposed substantially opposite a feed perforated portion of the strip, tensioning support means operative on said bearing member at spaced points therealong to longitudinally tension the same, an elongated tubular feed shuttle having its bore engaged on said bearing member between said spaced points for reciprocatory strip feed and return movement and oscillatory strip perforation engaging and disengaging movement of said shuttle along and about said bearing member, said shuttle being provided with a feed tooth at an upper portion thereof and extending radially of said bore and adapted for strip perforation engaging and disengaging movement with said oscillatory movement of said shuttle in an arcuate path extending predominantly edgewise of the strip, means operative on said shuttle at a lower portion thereof to effect strip feeding movement of the same, and packing means surrounding and slidably engaging said shuttle between said upper and lower portions to provide a lubricant barrier.
